UNITED STATES PATENT OFFICE.

DANIEL M. PFAUTZ, OF GERMANTOWN, PENNSYLVANIA, ASSIGNOR OF ONE-HALF TO WILLIAM H. TIGERMAN, OF PHILADELPHIA, PENNSYLVANIA.

ADJUSTABLE STAIRWAY FOR SUSPENDED RAILWAY-CARS.

No. 841,653.

Specification of Letters Patent.

Patented Jan. 15, 1907.

Application filed May 19, 1906. Serial No. 317,689.

To all whom it may concern:

Be it known that I, DANIEL M. PFAUTZ, a citizen of the United States, residing at Germantown, in the county of Philadelphia and State of Pennsylvania, have invented certain new and useful Improvements in Adjustable Stairways for Suspended Railway-Cars, of which the following is a specification.

10 My invention has relation to cars adapted to be suspended from elevated-railway structures, and in such connection it relates to an adjustable stairway adapted to form a means of exit for passengers from suspended or elevated cars and as a means of entrance to said cars.

The principal objects of my present invention are, first, to provide a simple and efficient adjustable stairway for suspended or elevated railway-cars; second, to provide the platform of a car with a stairway, one end of which may be lowered to connect the car with a street or roadway and to form not only a means of exit, but also of access to the car; third, to provide the adjustable stairway and car with a mechanism adapted to raise and lower the free ends thereof, and, fourth, to provide the raising and lowering mechanism with a locking device adapted to hold the stairway in a raised or inoperative position parallel to the bottom of the car and to permit of the instant lowering of the stairway in case of accident or otherwise.

The nature and scope of my present invention will be more fully understood from the following description, taken in connection with the accompanying drawings, forming part hereof, in which—

Figure 1 is a sectional view of the upper portion of an elevated structure, illustrating in side elevation a car and in full and dotted lines the operative and inoperative positions of a stairway hinged to said car, embodying main features of my present invention.

Fig. 2 illustrates in end elevation a portion of the elevated structure and the car and the stairway in its lowered or operative position.

Fig. 3 is a detail view, enlarged, illustrating in end elevation the mechanism for raising and lowering the same. Fig. 4 illustrates, partly in side elevation and partly in section, the mechanism for operating the stairway; and Fig. 5 is a side elevational view of a lock-

ing device for the mechanism for raising and lowering the stairway.

Referring to the drawings, *a* and *a'* represent columns suitably connected to and supported by pedestals *a²*, located back of the curb-line and adjacent to the sidewalks *a⁴* of a street or roadway *a⁶*. To a pair of oppositely-arranged columns *a* and *a'* is suitably secured a cross-girder *a⁷*. Midway between the columns *a* and *a'* and a proper distance apart are arranged longitudinal girders *b* and *b'*, suitably secured to said cross-girder *a⁷*, which supports the same. These longitudinal girders *b* and *b'* are furthermore rigidly connected with the cross-girder *a⁷* by brackets *a⁸* and *a⁹*, and a similar pair of brackets *a¹⁰* and *a¹¹* connect the cross-girder *a⁷* with the supporting-columns *a* and *a'*. To the lower inner flanges *b⁶* and *b⁷* of the longitudinal girders *b* and *b'* are secured rails *b⁸* and *b⁹*. Upon these rails are adapted to travel the wheels *d¹⁰* and *d¹¹* of a truck *d'*. The truck *d'* supports a car *d*, provided with rear and front platforms *d²* and *d³* and dashboards *d⁴* and *d⁵*.

In order to permit passengers to enter or leave the car *d*, suspended from the elevated structure outside of the stations designated for this purpose, and especially to afford a ready means to leave the car in case of accident, the same is provided with a movable stairway *g*, hinged at the point *g'* to the platform *d³* of the car *d*. In the normal position of the stairway *g* the same occupies the position indicated in full lines in Fig. 1, parallel to the bottom of the car *d*, and occupying this position when not in use does not in any manner interfere with the proper operation of the car. The rear and front platforms *d²* and *d³* of the car *d*, however, are laterally extended, as shown in Figs. 2 and 3, to afford ready access to the stairway *g*. The free end of the stairway is supported by a bail-like bracket *g²*, which by means of a rope or chain *g³* is connected with a drum *g⁴*, secured to the car *d*, upon which the cord or chain *g³* is wound or unwound in the raising or lowering of the free end of the stairway *g*. To the drum *g⁴* is secured a sprocket-wheel *g⁵*, which by means of a sprocket-chain *g⁶* is connected with a sprocket-wheel *g⁷*, mounted on a shaft *g⁸*. The stairway is held in a raised or inoperative position by a ratchet-wheel *g⁹*, se-

cured to the sprocket-wheel g^7 , and by bringing the pawl g^{10} out of engagement with the ratchet-wheel g^9 the stairway may be instantly lowered into the position indicated by dotted lines in Fig. 1, in which the same with its free end rests directly upon the street or roadway a^6 . In this position the stairway g , in conjunction with the extended platforms of the car, form a ready and comparatively comfortable means of leaving the car outside of a station. The stairway g can be readily raised by turning the shaft g^8 and sprocket-wheel g^7 by means of the crank-arm g^{11} , which movement of the sprocket-wheel g^7 by the chain g^6 is transmitted to the drum g^4 , upon which the cord or chain g^3 is wound.

Having thus described the nature and objects of my invention, what I claim as new, and desire to secure by Letters Patent, is—

- 20 1. In an elevated-railway system, in combination with a car, a platform arranged at each end of said car and extending laterally beyond the body thereof, a stairway pivoted at one end to one of said platforms and resting in an inoperative position parallel to the body of said car and between said platforms, and means for connecting the free end of said stairway with the body of said car and for raising and lowering the same.
- 25 2. In an elevated-railway system, in combination with a car, a platform arranged at

each end of said car and extending laterally beyond the body thereof, a stairway pivoted at one end to one of said platforms and resting in an inoperative position parallel to the body and between the platforms of said car, a bail secured to the free end of said stairway, a drum secured to said car, means connecting said bail with said drum, and means for actuating said drum.

3. In an elevated-railway system, in combination with a car, a platform arranged at each end of said car and extending laterally beyond the body thereof, a stairway pivoted at one end to one of said platforms and resting in an inoperative position parallel to the body and between the platforms of said car, a bail secured to said stairway, winding means for raising and lowering the free end of said stairway secured to said car, means for operating said winding means, and locking means for the operating means of said stairway.

In testimony whereof I have hereunto set my signature, in the presence of two subscribing witnesses, this 18th day of May, A. D. 1906.

DANIEL M. PFAUTZ.
